DESIGN FOR A COMBINED GAME BOARD AND PERIODICAL SUPPORT

James Glenn Rolley, New York, N. Y.

Application October 28, 1944, Serial No. 116,018

Term of patent 14 years

(Cl. D33—10)

To all whom it may concern:

Be it known that I, James G. Rolley, a citizen of the United States of America, residing at New York, in the county of New York and State of New York, have invented a new, original, and ornamental Design for a Combined Game Board and Periodical Support, of which the following is a specification, reference being had to the accompanying drawing, forming part thereof.

Figure 1 is a front elevational view of a combined game board and periodical support, showing my new design.

Figure 2 is an end elevation thereof.

Figure 3 is an elevational view showing the opposite side of the device.

Figure 4 is a cross section on the line A—A of Figure 1.

Figure 5 is a cross section on the line B—B of Figure 1.

I claim:

The ornamental design for a combined game board and periodical support, as shown.

JAMES GLENN ROLLEY.
